CLAIM

The ornamental design for a camcorder case with waist straps, as shown and described.

DESCRIPTION

FIG. 1 is a front perspective view of a camcorder case with waist straps showing my new design with the top flap and front pocket in an open position; the broken lines representing environment and forming no part of the claimed design; FIG. 2 is a front elevational view thereof, shown in a closed position;

FIG. 3 is a rear elevational view of FIG. 2;

FIG. 4 is a right side elevational view of FIG. 2;

FIG. 5 is a left side elevational view of FIG. 2;

FIG. 6 is a top plan view of FIG. 2; and,

FIG. 7 is a bottom plan view of FIG. 2.
